(57) **CLAIM**

We claim the ornamental design for a portable power supply, as shown and described.

DESCRIPTION

FIG. 1 shows a perspective view of a portable power supply of the present invention;

FIG. 2 shows a front view of the portable power supply of FIG. 1;

FIG. 3 shows a rear view of the portable power supply of FIG. 1;

FIG. 4 shows a top view the portable power supply of FIG. 1; FIG. 5 shows a bottom end view of the portable power supply of FIG. 1;

FIG. 6 shows a right side view of the portable power supply of FIG. 1; and,

FIG. 7 shows a left side view of the portable power supply of FIG. 1.

The broken lines shown represent unclaimed subject matter and form no part of the claimed design.
